PILE ELEVATOR FOR SHEET FEEDING
MACHINES

Morris S. Gudger, New York, N. Y., and Frederick W. Seybold, Elizabeth, N. J., assignors to American Type Founders, Inc., Elizabeth, N. J., a corporation of New Jersey

Application June 29, 1939, Serial No. 281,990

13 Claims. (Cl. 271—62)

This invention relates to feeding sheets and more particularly to mechanism for elevating piles of sheets to the proper point for separating and forwarding them, and to controlling means for said mechanism.

The general object of the invention is the provision of a novel and improved pile elevator for sheet feeders which may be either manually or power operated, and which is provided with certain automatic controls for regulating the height of the pile during the feeding operation, and for preventing movement of the elevator beyond permissible limits in either direction of movement.

Although the principles of the invention may be applied to many different types of sheet feeding devices, the illustrative embodiment is adapted to a feeding mechanism similar in all respects to the one which forms the subject of our copending application, Serial No. 281,989, filed of even date herewith, to which reference may be had for further details which are not strictly essential to a proper disclosure of the present invention.

In the preferred embodiment, the invention contemplates the provision of supporting frames upon which the platforms carrying the piles of sheets rest and which are adapted to be raised and lowered by means of endless chain hoists operatively connected to the main frame of the feeder. The chains are provided at intervals with lugs with which hooks on the frames are adapted to engage, and the arrangement is such that one platform may be loaded with sheets while the last of the sheets on a previously loaded platform are being fed, and when the previous pile is depleted, the platform may be readily removed from the hoist so that the new pile may be brought into position for feeding.

The raising and lowering of the pile to feeding position may be accomplished manually or by power operated means, a clutch being provided for changing over the driving connections.

Novel means are provided for automatically raising the pile by very small increments while the sheets are being fed therefrom, in order to maintain the successive top sheets of the diminishing pile in proper relation to the separating and forwarding elements; and novel stop mechanism is also provided for limiting the extreme upward or downward movement of the pile hoisting mechanism to prevent damage to the machine which would occur if the platforms, with or without a pile of sheets, were carried beyond the stop devices into contact with the feeding

members at the top or with the floor at the bottom of the machine.

Other objects and features of novelty will be apparent from the following specification when read in connection with the drawings in which one embodiment of the invention has been illustrated by way of example.

In the drawings,

Figure 1 is a view in rear elevation of a machine embodying the principles of the invention, certain portions being shown in section;

Figure 2 is a top plan view of the machine;

Figure 3 is a transverse vertical sectional view on an enlarged scale of a portion of the drive shaft for the pile elevating mechanism;

Figure 4 is a fragmentary view in vertical section of the clutch operating shaft;

Figure 5 is a detail sectional view taken on line 5—5 of Figure 4;

Figure 6 is a longitudinal sectional view of the upper portion of the device, taken on line 6—6 of Figure 1;

Figure 7 is a fragmentary view in side elevation of certain of the parts shown in Figure 6, but in shifted position;

Figure 8 is a fragmentary view in side elevation of the pile elevator controlling feeler and associated mechanism, certain parts being shown in longitudinal vertical section;

Figure 9 is a view in rear elevation of the same elements, portions being shown in transverse vertical section;

Figure 10 is a view of a portion of the same mechanism in horizontal section, taken substantially on line 10—10 of Figure 8;

Figure 11 is a view in perspective of certain elements of the feeler mechanism, other parts being removed for the sake of clearness of illustration;

Figure 12 is an enlarged view, chiefly in side elevation, of the limit switch operating mechanism;

Figure 13 is a view in elevation of the same parts shown in Figure 12, as seen from the right-hand side of that figure; and

Figure 14 is a diagram of the electrical connections involved in the control of the pile elevator motor.

In Figures 1 and 2 of the drawings the frame of the novel feeding device is very clearly shown and will be seen to comprise the upper frame casting 10 which is supported upon the four legs 11, each of the legs preferably formed of channel members. The legs rest upon the floor 12 adjacent a pit or depression 13 into which the plat-

form supporting cross bars 15 are adapted to be disposed so that the platforms 16 which support the pile of sheets S may be more readily placed upon and removed from the bars 15.

5 The bars 15 are preferably employed in pairs and each is provided at its opposite ends with bifurcated hooks 18 which are adapted to straddle the chains 19 and engage pairs of oppositely projecting lugs 20. These lugs are secured at equal 10 intervals along the hoisting chain 19, preferably at intervals equal to one-third the length of the chain, depending upon the distance of the feeding mechanism from the floor. The chain hoists are duplicated upon each side of the apparatus 15 as clearly shown in Figure 1 and pass around sprocket wheels 22 carried upon the shafts 23 which extend between the lower portions of the legs upon each side of the frame, and the upper portions of the chains are trained around the 20 sprockets 24 which are secured upon the shafts 25 which are provided with bearings in the upper frame casting 10.

An elevator drive shaft 27 is rotatably mounted in horizontal position upon the top of the 25 frame 10 and is provided adjacent its ends with the worms 28 which mesh with the worm wheels 29 which are keyed to the shafts 25 at points intermediate the lengths thereof. The worms 28 are covered by the casings 30. Various means 30 for continuously and intermittently actuating the pile elevators through the drive shaft 27 are provided and will be described presently.

The pile of sheets S is raised by means of the 35 chains from the loading position shown in dotted lines in Figure 1 to the feeding position shown in full lines, wherein the sheets are successively separated and forwarded from the pile S toward the feed rolls 32 which are furnished with the drop rolls 33 supported by means of 40 brackets 34 carried upon the shaft 35. The feed rolls 32 are carried by the shaft 36 which is provided with a sprocket 37 connected by a chain 38 with the sprocket 39 upon the transverse shaft 40. This shaft is connected by means of the 45 bevel gearing 41 with the forwardly extending shaft 42 which is adapted to be driven from the processing machine to which the sheets are ultimately fed, so that the feeding cycle will be synchronized with the cycle of operation of the 50 processing machine.

The separating and feeding of the sheets from the pile S is accomplished by means of the forward suction gripper feeders 45 which are mounted for oscillation in a vertical plane, and 55 the rear suction gripper separators 46, which are adjustably secured to the forwardly and rearwardly adjustable transverse shaft 48, all as clearly disclosed in our copending application, Serial No. 281,989.

60 In order to maintain the top of the pile at the proper elevation for access by the feeding members, the pile elevator is moved upwardly by small increments effected by the intermittent actuation of the drive shaft 27 through the ratchet wheel 50 which is keyed to the shaft 27. A bell crank lever 51 is rotatably mounted upon the shaft 27 adjacent the ratchet wheel 50 and one of its arms is provided with a pivoted pawl 52, a tooth of which is adapted to engage the 65 ratchet. The longer arm of the bell crank 51 is pivotally connected as at 54 with the depending link 55 which extends through an opening in the top of the frame casting 10 and is connected at its lower end with the end of a lever 56 which is pivotally mounted upon the shaft 70

58. The lever 56 is caused to oscillate by means of the eccentric cam 60 carried upon the cam shaft 61 and contacting the roller 62 carried by the end of the arm 63 which is rigid with the lever arm 56. A third arm 64 extending from this compound lever has a rod 65 pivoted thereto, and this rod extends through an opening in the stud 66. A coil spring 67 is compressed between the stud 66 and a shoulder 68 on the rod 65, and serves to maintain the cam roller 62 in 10 engagement with the cam 60.

Upon the outer end of the cam shaft 61 there is fixed a sprocket 70 which is connected by means of the chains 71 with the sprocket 72 on the end of the feed roller shaft 36. Upon the 15 inner end of the cam shaft there is provided a sprocket 75 which carries a chain 76 for driving the rotary valve mechanism which controls the suction gripper devices, all as fully described in the copending application to which reference 20 has been made.

Obviously, upon rotation of the cam shaft 61 the lever 56 will be oscillated in a vertical plane so as to drive the ratchet 50 and rotate the elevator drive shaft 27. In order to control the 25 rate of elevation in accordance with the removal of the sheets by means of the suction grippers, certain mechanism is provided which is shown in Figures 1 and 6 of the drawings and illustrated in detail in Figures 8 to 11 inclusive. A vertical post 80 depends from the top of the frame casting 10 substantially centrally of the pile S.

In the same vertical longitudinal plane with the post 80 there is disposed a bracket 81 which is secured to the transverse shaft 48 which also 35 serves to support the rear suction grippers 46. The bracket 81 is provided with spaced forwardly extending ears 82 and 83 through which is slidably positioned the substantially cylindrical casing 84. Received within the lower end of this 40 casing is the plunger 85 which carries the contact roller 86 upon its lower end. A pin 87 projects from the plunger 85 and is guided within the slot 88 formed in the wall of the casing 84 in order to maintain the roller 86 in the longitudinal position. Projecting from the upper end of the plunger 85 and guided through an opening in the upper wall of the casing 84 is the rod 89. A collar 90 is adjustably secured to the rod 89 in order to limit the downward movement of 50 the rod and the plunger through the casing. The plunger and roller 86 are urged in a downward direction by means of the coil spring 91 which is adapted to be compressed between the upper wall of the casing 84 and the top of the plunger 55 85. The free upward movement of the casing 84 in the bracket is limited by abutment of the collar 84 with the arm 82, any abnormal further movement being resiliently resisted by the compression of the spring 91.

Intermediate its length the casing 84 is provided with flat surfaces which are milled thereon for the reception of the ends of the bifurcated lever 92. This lever is secured to the cylindrical end portion 93 of the generally squared rock 65 shaft 94 which is received within the boss 95 of the bracket 81, the rock shaft 94 extending freely through a round opening in the post 80. A lever 96, retained against the post 80 by means of the plate 103 secured as at 104, has a squared 70 opening which receives the rock shaft 94 and is pivotally connected to the lower end of the substantially vertically extending link 97 which is in turn pivoted at its upper end to the end of the horizontal lever 98, this lever being se- 75

cured to the shaft 99 upon the outer end of which is carried the stop member 100. The shaft 99 is carried by the bracket 101 secured to the underside of the top of the frame 10.

5 The stop member 100 is adapted to be moved into and out of a position directly above the abutment 102 formed on the ratchet operating lever 56. Thus, as the pile of sheets rises through the step by step operation of the pile elevator by 10 means of the ratchet device, the feeler roller 86, plunger 85, and casing 84 will be moved upwardly and the rock shaft 94 rotated in a clockwise direction as viewed in Figure 9, this causing the stop member 100 to be moved to the left in Figure 6 and thus block the operation of the ratchet lever until enough sheets have been fed from the pile to lower the upper level thereof sufficiently to permit the feeler roller 86 to drop and withdraw the stop member 100 from above the abutment 102.

There is secured upon the shaft 99 a substantially triangular abutment element 104, the legs 105 of which are adapted to strike against the lower face 106 of a stationary portion of the frame 10 and thus to limit the extent of oscillation of the stop member 100 to prevent warping or twisting of the operating linkage 96, 97, 98, which, it will be observed, operates in two different planes.

As already noted, the rear suction grippers 30 which serve to separate the sheets from the pile at their rear edges are carried by the transverse shaft 48 and are adjustable forwardly and rearwardly in accordance with the length of the sheets being fed. This adjustment is readily effected 35 by means of the clamping brackets 108 (Figure 1) which may be positioned at any point along the side rods 109, carried upon either side of the supporting frame 10. Thus it will be seen that not only are the rear grippers 46 adjustable in this 40 manner, but the feeler control device for the pile elevator is similarly adjustable, since this device is carried upon the same shaft 48. By means of the extensible connection between the rock shaft 94 and the linkage which operates the stop element 100, a permanent operative connection is 45 maintained regardless of the adjusted position of the feeler device.

For the purpose of raising the pile of sheets to feeding position or lowering the platform to loading position, optionally usable manual or power devices are employed. If it is desired to raise the elevator by manual means, a hand wheel 110 carried upon the left-hand end of the drive shaft 27, as seen in Figure 1, is rotated. This 50 means is generally employed when the elevator is to be moved through short distances as for purposes of adjustment.

In order to raise the pile by power means, there is provided the electric motor 115 whose 55 shaft 116 is connected by means of the chain 117 to the sprocket 118 fixed to the tubular countershaft 120 which surrounds the drive shaft 27 at its central portion and is provided with bearings 121 mounted upon the frame 10. A clutch indicated generally by the reference numeral 125 is provided for connecting the countershaft 120 to the drive shaft 27. A clutch element 126 is keyed 60 by means of the set screw 127 to the countershaft 120 and a slicable clutch element 128 is splined 65 as at 129 to the shaft 27. The movable clutch element 128 is provided with the grooved extension 130 with which the yoke 131 is adapted to cooperate. The operating yoke 131 is rotatably mounted with respect to the control rod 135 and 70 is prevented from sliding relatively thereto by

means of the sleeves 136. The rod 135 is slidably and rotatably carried in the bearing 138 and in the spaced bearing members 140 carried by the frame. A bifurcated actuating lever 142 is pivoted to a bracket 143 at one end of the frame and surrounds the end of the shaft or rod 135 between the two sleeves 144. It will be seen that by operating the lever 142 the rod 135 is shifted longitudinally and will effectively clutch or disconnect the motor driven countershaft 120 and the elevator drive shaft 27. 10

However, it is important that the automatic ratchet drive of the shaft 27, actuated in accordance with the sheet feed, be disconnected when power is applied to the shaft 27. This is effected 15 by means of the cam plate 150 which is provided with a curved surface 151 adapted to contact with the pin 152 on the ratchet pawl 52 and displace the pawl from engagement with the ratchet wheel 50. This cam 150 is connected by means 20 of the link 154 with the arm 155 which is keyed as at 156 to the rod 135, as clearly shown in Figures 4 and 5 of the drawings. By rotation of the rod 135 by means of the hand crank 158, the cam may be thrown so as to disengage the ratchet 25 during the operation of the motor drive. In order to insure that the clutch 125 cannot be actuated to connect the motor to the shaft 27 until the ratchet has been disconnected, a keyway 160 is provided in one of the bearing brackets 140, the 30 keyway being disposed in such angular position that the key 156 carried by the shaft 135 cannot enter it until the shaft is rotated sufficiently to disengage the ratchet pawl. When this is accomplished, then the shaft 135 can be moved longitudinally to actuate the clutch 125. 35

A vacuum pump 162 is connected by means of the sprocket gearing 163 with the countershaft 120 for operation by the motor 115. This vacuum pump provides the necessary suction for the pneumatically operated feeding grippers. 40

In order to limit the extreme upward or downward movement of the pile elevating mechanism, there is provided a cam operated electrical trip or limit switch indicated generally by the reference numeral 170 and shown in considerable detail in Figures 12 and 13 of the drawings. A bracket 172 is secured as by means of the bolts 173 to a portion of the frame casting 10 adjacent the point where the legs 11 are secured thereto. 45 This bracket supports the actual switch mechanism concealed in the housing 174 and actuated by contact with the projecting plunger or button 175. Pivoted upon the pintle 176 carried by the bracket 172 is a switch actuating cam member 178, this member being provided with an upper curved portion 179 adapted to contact the button 175. A rod 180 is pivotally connected to the cam member 178 as at 181 and the lower end of the rod passes through an opening in the curved arm 182 which projects from the movable blade or actuator 183. Adjustable nuts 184 are threaded upon the end of the rod 180 and a spring 185 extends between the arm 182 and the shoulder 186 on the rod 180 in order to hold the cam 178 50 and the actuator 183 in the normal position shown in solid lines in Figure 8. 55

This limit switch arrangement is disposed adjacent the outside of the chain loop and is adapted to be actuated when the hoisting mechanism 70 has moved a platform to an upper or lower limiting point. Thus, as the platform nears the upper limit, the chain 19 moves downwardly through the stop device which is adapted to be actuated when one of the lugs 20 passes down- 75

wardly within the throat formed between the stationary guide member 188 and the curved cam surface 189 of the movable cam or actuator member 183. As the lug moves the member 183 outwardly to its dotted line position, the cam member 178, by means of the rod 180, is moved upwardly so as to contact and move the plunger or trip button 175 and open the limit switch in the casing 174. This immediately stops the motor and prevents further elevation of the device. Of course, in preventing the lowering of the platforms beyond the set limit, the lug will enter the arrangement from the bottom and move past the inclined surface 190 of the cam actuator 183 to effect the opening of the switch.

After the motor circuit has been broken by means of this trip arrangement, it can be restored by pulling out the knob 192 which is connected by means of the shank 193 to the cam member 178 as at 194, which action will compress the spring 185 so as to allow the cam member 178 to move downwardly and release the contact button 175. While holding this knob outwardly, the motor may be started in either direction by manipulating one of the main motor switches.

The function of this stop mechanism is to prevent damage to the pile hoist devices which would occur if the pile carrying bars were carried beyond the stops so as to interfere with the feeding mechanism at the top of the machine, or to prevent the collision of descending lugs 20 on the chain with bars 15 lying in the pit 13.

In Figure 10 of the drawings, there is shown a diagram which fully explains the positively operated and emergency connections for energizing and de-energizing the motor. The motor is indicated diagrammatically at M, and the three-wire main line is indicated at L. Solenoids N and N' are connected by the shaft 200 to which the switch arms 201, 202, 203, 204, and 205 are connected. The arms 201, 202, and 203 are connected with the three terminals of the motor M and are adapted to be alternatively placed in contact with the switch points which are connected to the outside wires of the three-wire circuit L in order to operate the motor in forward and reverse directions. When the push button A is pressed, the solenoid N' is actuated to move the switch rod 200 toward the right in Figure 10 and will energize the motor in the forward direction to elevate the pile. The solenoid N is adapted to be energized by operation of the push button B to effect the lowering of the pile. By means of the switch arms 204 and 205, the "down" circuit and the "up" circuit are broken by the corresponding operation of the "up" and "down" solenoids.

The push button C is a "stop" switch which serves to disconnect the motor circuit no matter in which direction it is then operated. The limit switch which is contained in the housing 174 is indicated at D in the diagram of Figure 10, and is disposed in the same "stop" circuit as the button C.

There is inserted in the "up" circuit connected with the solenoid N' a mercury switch F which is contained in the box 210 carried upon the outer end of lever 211, which is fulcrumed at 212 on the brackets 213 secured to the post 80 at an intermediate point. The inner end of the lever 211 is pivotally connected to the vertical links 214, which are pivoted at their lower ends to the forwardly projecting end of the angular lever arm 215. This arm 215 is fulcrumed upon

the lower end of the post 80 at 216 and carries the roller 220 upon its rear bifurcated end.

This roller is adapted to be contacted by the top sheet of the pile, either when being lifted and forwarded in the normal way or when the pile carrying platform is being raised by power. The raising of the roller 220 beyond a certain point will cause the mercury switch F in the box 210 to open, breaking the motor circuit and preventing the moving of the pile of sheets, by power, into interference with the height gauge mechanism. When this contact is broken, the motor may still be operated, but in a downward direction only.

By means of the present invention there has been provided novel and efficient means for automatically or positively actuating the pile elevator mechanism of the sheet feeder and there are also provided various safety devices for preventing accidental damage to the machine or the operator.

Various changes and modifications may be made in the embodiments illustrated and described herein without departing from the scope of the invention as defined by the following claims.

Having thus described the invention, what is claimed as new and desired to be secured by Letters Patent is:

1. In a sheet feeder of the class described, or the like, having means for successively feeding sheets from a pile, the combination of a supporting frame, a pile elevator, a driving shaft for said pile elevator, a ratchet and pawl device adapted to rotate said shaft to gradually raise said pile elevator during feeding, a motor and transmission driven thereby, a clutch for connecting and disconnecting said transmission with respect to said shaft, and a manually operable rotatable and reciprocable control rod disposed adjacent said driving shaft and operatively connected with both said clutch and said ratchet and pawl device.

2. In a sheet feeder of the class described, or the like, having means for successively feeding sheets from a pile, the combination of a supporting frame, a pile elevator, a driving shaft for said pile elevator, a ratchet and pawl device adapted to rotate said shaft to gradually raise said pile elevator during feeding, a motor and transmission driven thereby, a clutch for connecting and disconnecting said transmission with respect to said shaft, a manually operable control rod disposed adjacent said driving shaft and operatively connected with both said clutch and said ratchet and pawl device, and means for preventing the actuation of said rod to connect said clutch until said ratchet and pawl device is locked out of operation, and for preventing the unlocking of said ratchet and pawl device until said clutch is disconnected.

3. In a sheet feeder of the class described, or the like, having means for successively feeding sheets from a pile, the combination of a supporting frame, a pile elevator, a driving shaft for said pile elevator, a ratchet and pawl device adapted to rotate said shaft to gradually raise said pile elevator during feeding, a motor and transmission driven thereby, a clutch for connecting and disconnecting said transmission with respect to said shaft, a manually operable control rod disposed adjacent said driving shaft and operatively connected with both said clutch and said ratchet and pawl device, whereby rotation of said rod in opposite directions serves to respectively

block and free said ratchet and pawl device, and reciprocation of said rod in opposite directions serves to respectively connect and disconnect said clutch, and spline means for preventing reciprocation of said rod while being rotated to free said ratchet and pawl device and for preventing rotation of said rod while being reciprocated to engage said clutch.

4. In a sheet feeder of the class described, or 10 the like, having means for successively feeding sheets from a pile, the combination of a supporting frame, a pile elevator, a driving shaft for said pile elevator, a ratchet and pawl device adapted to rotate said shaft to gradually raise said pile 15 elevator during feeding, a motor and transmission driven thereby, said transmission including a tubular shaft surrounding said driving shaft, a clutch for connecting and disconnecting said tubular shaft with respect to said shaft, and a 20 manually operable control rod disposed parallel with said driving shaft and operatively connected with both said clutch and said ratchet and pawl device.

5. In a sheet feeder of the class described, or 25 the like, a supporting frame, a pile elevator, a driving shaft for said pile elevator, a tubular shaft surrounding said driving shaft and rotatable relatively thereto, a motor operatively connected with said tubular shaft for rotating the 30 same, a clutch for connecting and disconnecting the two shafts, an air pump associated with said sheet feeder, and operative connections between said pump and said tubular shaft for driving said pump.

35 6. In a sheet feeder of the class described, having mechanism at the upper portion of said frame for separating and feeding the sheets from a pile, the combination of a supporting frame, a pile elevator, said elevator comprising a pile supporting platform and chains for lifting the same, power means for raising and lowering said elevator, a safety cut-out device carried by the frame adjacent one of the chains, and an actuating element carried by said chain for tripping 40 said cut-out device and thus rendering said power means ineffective at a predetermined point in the travel of the chain.

7. In a sheet feeder of the class described, having mechanism at the upper portion of said frame 50 for separating and feeding the sheets from a pile, the combination of a supporting frame, a pile elevator, said elevator comprising a pile supporting platform and chains for lifting the same, power means for raising and lowering said elevator, a safety cut-out device carried by the frame adjacent one of the chains, an actuating element carried by said chain for tripping said cut-out device and thus rendering said power means ineffective at a predetermined point in 55 the travel of the chain, and manually operated means for nullifying the effect of the cut-out device.

8. In a sheet feeder of the class described, having mechanism at the upper portion of said frame 60 for separating and feeding the sheets from a pile, the combination of a supporting frame, a pile elevator, said elevator comprising a pile supporting platform and chains for lifting the same, an electric motor for raising and lowering said elevator, a source of electric current, starting and stopping circuits connecting said motor with said source of current, manually actuated starting and stopping switches in said respective circuits, a safety cut-out switch in said stopping circuit, a 65 trip for actuating said safety switch, said trip

carried by said frame adjacent a portion of the elevator mechanism and adapted to be actuated thereby at a predetermined point during its travel, and manual means for nullifying the effect of said trip and reversing the actuation of said 5 switch, while said starting switch is actuated to move the elevator further.

9. In a sheet feeder of the class described, having mechanism at the upper portion of said frame 10 for separating and feeding the sheets from a pile, the combination of a supporting frame, a pile elevator, means for raising said pile elevator step by step as the sheets are removed from the pile, feeler mechanism for controlling the operation 15 of said raising means, said mechanism comprising a movable stop element for alternatively blocking and freeing the movement of said raising means, said element disposed at a relatively fixed point on the frame, a vertically movable feeler element adapted to be lifted by the pile at a predetermined point in its upward movement, said element being adjustable longitudinally of the frame 20 for piles of sheets of different lengths, and an extensible operative connection between said feeler element and said stop element.

10. In a sheet feeder of the class described, having mechanism at the upper portion of said frame for separating and feeding the sheets from a pile, the combination of a supporting frame, 30 a pile elevator, means for raising said pile elevator step by step as the sheets are removed from the pile, feeler mechanism for controlling the operation of said raising means, said mechanism comprising a movable stop element for alternatively blocking and freeing the movement of said raising means, said element disposed at a relatively fixed point on the frame, a vertically movable feeler element adapted to be lifted by the pile at a predetermined point in its upward movement, said element being adjustable longitudinally of the frame 35 for piles of sheets of different lengths, and an extensible operative connection between said feeler element and said stop element, a transverse shaft adjustably supported by said frame above the pile and means for supporting one of the sheet handling elements of said separating and forwarding mechanism upon said shaft, and means for supporting said feeler element from said same shaft for simultaneous adjustment.

11. In a sheet feeder of the class described, having mechanism at the upper portion of said frame for separating and feeding the sheets from a pile, the combination of a supporting frame, a pile elevator, means for raising said pile elevator step by step as the sheets are removed from the pile, feeler mechanism for controlling the operation of said raising means, said mechanism comprising a movable stop element for alternatively blocking and freeing the movement of said raising means, said element disposed at a relatively fixed point on the frame, a fixed post depending vertically from the top of said frame substantially above the center of the pile, a supporting bracket positioned rearwardly of said post 65 and adjustable longitudinally of the frame and of the pile, a vertically reciprocable feeler element carried by said bracket, a crank arm operatively connected with said feeler element, a rock shaft carried by said bracket and adapted to be 70 rotated by said crank arm, said rock shaft being rotatably and reciprocably supported by said post, whereby the feeler element may be adjusted longitudinally relatively to said post, and levers and linkage carried by said post and frame for opera- 75

tively connecting said rock shaft with said stop element.

12. A pile elevator for sheet feeders or the like, comprising, in combination, a supporting frame, 5 a pair of parallel endless chains trained about sprockets rotatably mounted at the upper and lower parts of said frame on horizontal axes, horizontal lugs on said chains extending from both sides thereof at spaced intervals, an elongated horizontally disposed bar having bifurcated hooks on the ends thereof adapted to straddle the chains and engage the lugs thereon, a pile supporting platform resting on said bar, a movable actuating element disposed in the path of certain 10 of said lugs for displacement thereby to control said elevator, said lugs thus functioning as supporting elements for the pile and as means for tripping said actuating means.
13. In a sheet feeder of the class described, 20 having mechanism at the upper portion of said frame for separating and feeding the sheets from a pile, the combination of a supporting frame, a pile elevator, means for raising said pile elevator step by step as the sheets are removed from the 25 pile, feeler mechanism for controlling the opera-

tion of said raising means, said mechanism comprising a movable stop element mounted for swinging movement for alternatively blocking and freeing the movement of said raising means, said element disposed at a relatively fixed point 5 on the frame, a fixed post depending vertically from the top of said frame above the pile, a supporting bracket positioned rearwardly of, said post and adjustable longitudinally of the frame and of the pile, a vertically reciprocable feeler element 10 carried by said bracket, a crank arm operatively connected with said feeler element, a rock shaft carried by said bracket and adapted to be rotated by said crank arm, said rock shaft being rotatably and reciprocably supported by said post, whereby 15 the feeler element may be adjusted longitudinally relatively to said post, and levers and linkage carried by said post and frame for operatively connecting said rock shaft with said stop element, and means for limiting the swinging movement 20 of said stop element in both directions to prevent excessive strain on the connecting linkage and levers.

MORRIS S. GUDGER.
